UNITED STATES PATENT OFFICE.

PETER FLANSBURG, OF MANISTEE, MICHIGAN.

COLLAPSIBLE SHIPPING CRATE OR BOX.

Application filed August 22, 1924. Serial No. 733,605.

To all whom it may concern.:

Be it known that PETER FLANSBURG, a citizen of the United States, residing at Manistee, in the county of Manistee and 5 State of Michigan, has invented new and useful Improvements in Collapsible Shipping Crates or Boxes, of which the following is a specification.

It is a purpose of the present invention 10 to provide, in a collapsible shipping crate or box, a construction wherein the sides are collapsible diagonally toward each other while the ends are collapsible respectively and hinged toward the sides, the top and 15 bottom lying flat while the collapsed sides and ends assume positions intermediate the top and bottom, enabling the crate or box to be arranged in small compass, so that a number of crates or boxes may be piled one 20 upon another.

Another purpose is to provide a crate including channel members for holding the slats or pieces of the sides, ends, top and bottom together, there being wire hinges 25 operatively connecting the channel members of the sides and ends for hinged connecting them, whereby they may be collapsed in the manner previously stated.

A further purpose is to provide improved 30 means consisting of channels and wires for hinged connecting the top and bottom to the sides, said wires being detachable to permit the top and bottom to be placed in registration with each other underneath the collapsed sides and ends.

A still further purpose is the provision of 35 a crate or box which is constructed to permit the crate or box to collapse and lie out flat. The top of the crate or box may be detached 40 so that it can be arranged to one side, the bottom being detachable, allowing the top to be disposed under or on top of the bottom, thereby permitting the sides and ends of the 45 crate to be collapsed and disposed in a collapsed position on the top and bottom, in which condition the crate can be shipped or transmitted to the sender.

It is to be understood that the particulars 50 herein given are in no way limitative and that, while still keeping within the scope of the invention, any desired modifications of detail and desired proportions may be made in the apparatus according to the circumstances.

The invention comprises further features 55 and combinations of parts to be hereinafter set forth, shown in the drawings and claimed.

In the drawings:

Figure 1 is a view in perspective of the 60 improved collapsible crate or box constructed in accordance with the invention, showing the same in an erect position for the purpose of receiving commodities to be shipped.

Figure 2 is a perspective view showing 65 the crate or box with the top or cover detached and disposed to one side.

Figure 3 is a perspective view showing 70 the top and bottom detached, the bottom resting upon the top, with the sides and ends collapsed in positions on the upper face of the bottom.

Figure 4 is a perspective view showing the 75 top and bottom detached at the upper and lower portions of the front of the crate, allowing the top and bottom to be laid out flat and the sides and ends of the crate collapsed.

Figure 5 is a longitudinal sectional view on line 5—5 of Figure 1.

Figure 6 is a transverse sectional view on line 6—6 of Figure 1.

Figure 7 is an enlarged detail perspective 80 view of one corner of the crate, showing clearly the hinge connection between a side and end.

Figure 8 is an enlarged detail view of the 85 hinge connection between the longitudinal edges of the top or bottom and the sides.

Figure 9 is a detail perspective view of one of the channel cleats.

Referring to the drawings, 1 designates 90 the crate or box as a whole and which comprises the sides 2 and 3, the ends 4 and the bottom and top 5 and 6. The sides and ends consist of slats 7 and 8, and 9 and 10 denote channel cleats. The channel cleats 9 receive 95 the ends of the slats 7. The cleats are constructed of sheet metal and are U-shaped and their bottoms have grooves or channels 11 and 12.

As previously stated, the cleats 9 and 10 are U-shaped and receive the ends of the 100 slats 7 and 8. The flanges of the U-shaped cleats are punched by means of any suitable tool, sufficiently to upset the metal on the inner ends of the flanges of the cleats, causing the metal around where the flanges are punched to form protrusions 13 which embed into the wood of the flats, thereby connecting 105

the cleats to the slats, making secure fastenings between the cleats and the slats.

The adjacent sheet metal cleats at each corner of the crate or box have adjacent slots 14 constructed transversely of the cleats. These slots receive U-shaped wires 15, the arms of which lie in the grooves or channels formed in the bottoms of the cleats. In this way, the sides and ends of 10 the crate or box are hingedly connected, there being no possible way of disconnecting the wires from the cleats unless it be by extreme pull used for straightening the wires or prying the flanges of the cleats 15 away from the slats, which manner of disconnection would not be employed unless it may be desired to destroy the crate entirely, or for the purpose of furnishing new cleats.

The bottom 5 comprises a plurality of 20 slats 16 which are connected by sheet metal cleats 17 which are fastened to the slats 16 in a similar manner to the fastening of the cleats to the slats of the sides and ends.

The top 6 is made up of a plurality of 25 slats or boards 18 closely adjoining one another, there being sheet metal U-shaped cleats 19 connecting the boards. The sheet metal cleats 19 are fastened to the boards in a manner similar to the fastening of the 30 cleats to the bottom slats and to the slats of the sides and ends.

Hinge members 20 and 21 (which are U-shaped) are carried by the longitudinal edges of the bottom and top, the fastening 35 of the hinge members consisting of any suitable means, preferably upset portions of the walls of the hinge members. These upset portions are caused to be formed by means of suitable punches in the metal to cause 40 protrusions 22 to be formed which embed in the wood of the bottom and top. These hinge members have their bottoms provided with grooves or channels which receive lateral arms 23 of U-shaped wires 24 and 25 45 which are detachably connected to the upper and lower slats of the sides.

Obviously, by detaching the wires from the slats, the bottom and top may be detached from the crate. It is possible to slide 50 the wires on the slats to disengage the arms from the channels or grooves in the bottoms of the U-shaped hinge members, in which case the bottom and top may be removed.

By moving the wires at the front *a* of the 55 crate or box in directions toward each other, that is, longitudinally of the crate, the bottom and top at their adjacent edge portions may be detached, allowing the top and bottom to lie out flat, then the sides and ends 60 may be collapsed, the sides toward each other diagonally and the ends toward the sides, as shown in Figure 4.

The top may be detached entirely and disposed to one side as in Figure 2.

The bottom and top may be detached entirely, the top disposed under the bottom, then the sides and ends may be collapsed hingedly, the sides toward each other and the ends toward the sides, and the collapsed sides and ends may then be disposed on the 70 upper face of the bottom. In this condition, the crate may be shipped back to the sender.

The invention having been set forth, what is claimed is:

1. A collapsible crate including side and 75 end pieces hingedly connected whereby the side pieces may collapse diagonally toward each other and the end pieces collapse respectively at the opposite sides, bottom and top pieces with detachable hinge connections 80 to the upper and lower edges of the side pieces, said detachable hinge connections comprising U-shaped hinge members with grooves or channels in their bottoms, and U-shaped wire hinge members detachably 85 slidably engaging the upper and lower slats of the side pieces and provided with arms engaging the grooves or channels in the bottoms of the U-shaped hinge members.

2. A collapsible crate including side and 90 end pieces, U-shaped cleats secured to the adjacent ends of the side and end pieces, the bottoms of the cleats having grooves and provided with transverse slots, U-shaped hinge members engaging through the slots 95 and having arms engaging in the grooves of the cleats, thereby hingedly connecting the sides and ends, and bottom and top pieces detachably hinged at both of their longitudinal edges to the upper and lower edges 100 of the sides pieces.

3. A collapsible crate including side and 105 end pieces, U-shaped cleats secured to the adjacent ends of the side and end pieces, the bottoms of the cleats having grooves and provided with transverse slots, U-shaped hinge members engaging through the slots and having arms engaging the grooves in 110 the bottoms of the cleats thereby hingedly connecting the side and end pieces, top and bottom pieces with detachable hinge connections to the upper and lower edges of the side pieces, said detachable hinge connections comprising U-shaped hinge members with grooves or channels in their bottoms, and U-shaped wire hinge members detachably 115

slidably carried upon the upper and lower slats of the side pieces and provided with arms engaging the grooves or channels in the bottoms of the U-shaped hinge members.

In testimony whereof he affixes his signature.

PETER FLANSBURG.
